US0D1031889S

(12) **United States Design Patent** (10) Patent No.: **US D1,031,889 S**
(45) Date of Patent: ** Jun. 18, 2024

(54) **GOLF CLUB HEAD**

(71) Applicant: **KARSTEN MANUFACTURING CORPORATION**, Phoenix, AZ (US)
(72) Inventors: **Travis D. Milleman**, Portland, OR (US); **Murphy R. Alexander**, Scottsdale, AZ (US)

(73) Assignee: **Karsten Manufacturing Corporation**, Phoenix, AZ (US)

(**) Term: **15 Years**

(21) Appl. No.: **29/865,118**

(22) Filed: **Jul. 8, 2022**

(51) LOC (14) Cl. **21-02**

(52) U.S. Cl.

USPC **D21/752**
